ECCENTRIC MOVING COIL ELECTRICAL
METERFrank Baranowski, Jr., Boston, Mass., assignor to
General Electric Company, a corporation of
New York

Application January 4, 1947, Serial No. 720,279

6 Claims. (Cl. 171—95)

1

My invention relates to electrical measuring instruments and in particular to direct current measuring instruments of the permanent magnet field type.

It is the object of my invention to provide an improved instrument of the type described in which parts heretofore used are eliminated, the cost is reduced, assembly requirements made less exacting, and the ratio of torque to weight increased, in an instrument which may use internal pivots and have a long scale.

My invention relates primarily to electrical measuring instruments of the permanent magnet field, direct current type which have a concentric air gap for one side of the moving coil across which the permanent magnet flux passes in a radial direction over a large portion of the arc of a circle, and sometimes designated concentric scale instruments. My invention concerns primarily the inner core structure and armature assembly, and another object is to provide a rugged internal pivot armature assembly unit which is easy to insert or withdraw from the field without disturbing the jeweled pivot adjustment.

In the usual prior art instrument of the general type to which my invention relates, a shaft usually extends through a central opening axially of the magnetic core and to which one side of the coil is secured, and with the pivots outside the ends of the coil. I depart from this arrangement. I use a coil the sides of which rotate in different circular gaps at different radii from the axis of rotation. The coil side of least radius rotates in a gap across which no flux passes and the coil side of largest radius rotates in the flux gap. In one form of my invention the magnetic core is generally C-shaped and may be permanently fastened to the outer yoke and permanent magnet field structure. A plug of nonmagnetic material carrying internal pivots for the armature is removably inserted in the central opening of the C-shaped magnetic core with the armature coil completely assembled thereon, such plug containing the nonflux-carrying gap for the short side of the armature coil.

In another form of my invention the magnetic core and internal pivot support are made in one piece of magnetic material which is removable with the armature.

In either case the arrangement provides outer magnetic core and inner internal pivot supporting parts concentrically arranged and outer and inner coil gaps concentrically arranged, with only the outer gap carrying the active flux. The arrangement provides a better balanced and lighter

2

armature assembly, a shorter axial instrument length, better protection for the instrument pivots, and more accessible lead-in spirals as compared to prior art instruments of the same general type.

The features of my invention which are believed to be novel and patentable will be pointed out in the claims appended hereto. For a better understanding of my invention, reference is made in the following description to the accompanying drawings in which Fig. 1 represents a plan view of a permanent magnet field instrument with a removable internal pivot plug and armature assembly in an instrument embodying my invention; Fig. 2 is a side view, partially in section, of the instrument of Fig. 1 with the armature coil pivoted therein; Fig. 3 is a plan view of a one-piece permanent magnetic field structure and core with a removable internally pivoted armature plug; Figs. 4 and 5 are plan and side sectional views of an internal pivot instrument embodying my invention having a removable inner magnetic core; Fig. 6 is a view taken on line 6—6 of Fig. 5.

The instruments to be described are of the type in which only one side of the armature coil rotates in a flux air gap and is effective in producing torque. Heretofore such instruments have employed a shaft to which the idle side of the armature coil was secured. According to my invention the shaft is eliminated and the axial space heretofore used as shaft space is occupied by internal pivots for the armature. The idle side of the armature coil is somewhat removed from the axis of rotation and rotates in an idle or fluxless air gap of small radius as compared to the effective torque air gap in which the other side of the coil rotates. In such an arrangement the shaft and the coil supports and insulation heretofore used in securing the armature coil to the shaft are eliminated. The structure for pivoting, balancing and alignment of the armature is simplified and reduced in size, weight, and cost and is somewhat more compact and rugged as compared to previous arrangements. In my invention the idle side of the coil helps to balance rather than contributing to unbalance of the armature, so that less counterbalancing is required and an exceptionally high ratio of torque to weight for this type of instrument is obtained.

Referring now to Figs. 1 and 2, 1 represents a permanent magnet of C-shape polarized radially as indicated by the N and S polarity marks thereon. The inner surface of the permanent magnet has secured thereto a soft iron pole shoe 2 forming one side of a C-shaped air gap 3 which is

circular and extends through an arc of some 300 degrees. A soft iron yoke 4 is secured to the outer surface of the permanent magnet and is integral with a radial tongue 5 and inner cylindrical core 6 also of magnetic material. The outer circular surface of the inner core defines the other or inner side of the circular air gap 3. This magnetic field is formed in one integral structure as by cast welding the pole shoe 2, yoke 4, tongue 5, and core 6 to the permanent magnet. It is practical to form the tongue 5 and inner core 6 of powdered, sintered magnetic material. The permanent magnet is polarized after assembly of the integral structure and no keeper or other precaution is necessary to prevent demagnetization, as no appreciable change of material in the air gap or reluctance to the flow of magnetic flux path crossing such gap can occur. Along one radius of the inner core a slot 7 is provided for the purpose of inserting one side of an armature coil through this opening. The slot 7 may be adjacent either side of the tongue 5 or in a zero center scale instrument, it may be directly opposite the tongue. After the armature coil is in place the slot 7 may be filled up, if desired, with a plug of magnetic material as shown at 42, Fig. 3, although this is not essential when the slot comes at one end of the air gap.

The armature coil 8 is rotatively supported in a die cast frame 10 which need not be of magnetic material. The frame 10 is in the form of a plug having a cylindrical outer surface of a size to fit snugly into the cylindrical opening in the C-shaped core 6. Frame 10 contains a radial slot 11 communicating with a C-shaped air gap space 12 for inserting and accommodating one side of the armature coil 8 therein. The plug or frame 10 also contains a hollow core part 13 secured to the outer shell part by a tongue 14. The frame 10 is provided with lateral extensions or tabs 15 at its top which, when the frame is inserted in place in the core as represented in Figs. 1 and 2, rests against the top of core part 6 and so that the frame may be fastened in place by screws 16. The core part 13 of the frame 10 contains an axial bore 17 for the purpose of holding jewel plugs 18 and 19 for rotatively supporting the armature coil 8 on internal pivots 20 and 21 as best shown in Fig. 2. The upper jewel 18 is immovably secured in the plug part 13, while the lower jewel may slide freely in the bore hole 17 unless held in place by a set screw 22. Between the jewels in the bore 17 is a light compression spring 23. The lower jewel may then be adjustable in the bore and, when properly adjusted, secured in place by the small set screw 22 which is contained in a threaded radial opening in the lower end of tongue part 14.

The armature coil 8 is pivoted on an axis which is central or concentric with respect to the plug frame 10, its air gap space 12 and the air gap 3, and the radii of its long and short sides designated 24 and 24a are the same as the mean radius of the gaps 3 and 12, such that the side 24 rotates freely in the outer magnetic gap 3 and the side 24a rotates freely in the idle or nonmagnetic gap 12. It is noted that rotation of the long side of the coil is limited to an angle of about 300 degrees by the tongue part 5, and that the short side of the coil is limited in rotation to the same 300 degrees by the tongue part 14. As pictured in Figs. 1 and 2, the coil 8 is at the center point of its range of rotation and may rotate about 150 degrees in either direction by reason of the fact that the radial tongue parts 75

5 and 14 are on opposite sides of the axis of rotation as are the long and short sides of the coil 8, thus permitting maximum rotation of the armature. It is evident that the arrangement permits the elimination of an armature shaft. The internal pivots shorten the axial length of the armature by the amount which such jewels and pivots would occupy if placed outside the armature. The armature coil is more nearly balanced than is the case where one side is placed next to the shaft and axis of rotation, so that less counterweight balancing is required. The long side 24 of the coil is preferably placed on the opposite side of the axis of rotation from the pointer which is shown at 25 and is secured to the top end of the coil 8, and helps to balance the weight of the coil about the axis of rotation. As a result only relatively small adjustable counterweights indicated at 26, 27, and 28 are required.

20 The weight indicated at 28 is made of a moisture absorbent material designed to absorb and give up moisture in the same relation as that of the armature coil 8, so as to maintain perfect balance under different humidity conditions. The lead-in spirals 29 and 30 for the armature coil have their inner ends secured in fixed relation to the outer ends of the coils near the axis of rotation. The disposition and accessibility of these lead-in spirals are no longer encumbered by external pivots and shaft extensions. The outer or normally stationary ends of the lead-in spirals are secured by a removable framework represented as made in two parts 31 and 32 fastened together by screws 33. The part 31 is secured by screws at 34 to the outer tongue portion of the magnetic circuit and has a lower arm 35 extending toward the axis of rotation to support the outer end of lead-in spiral 30 on a limb in a manner to permit initial rotary adjustment of such spiral.

40 The upper frame part 32 has a hollow circular part which extends around the axis of rotation and an inwardly extending tongue part 36 which supports a hub 37 on which the outer end of upper spiral 29 is rotatively secured. Linked with the rotary member of this spiral support is a crank arm 38 pivoted on a hub at 39 to serve as a zero adjustment device for the pointer. A scale plate 40 is secured above and in spaced relation to the field magnet as by means of studs and screws one of which is represented at 41 in Fig. 1. Other bolts may be provided through the field structure for mounting the instrument as desired.

55 When a magnetic plug such as shown at 42, Fig. 3, is used to close the gap at 7, the magnet will be polarized with the plug in place. It is evident that the field flux path is in general the same as in prior center core, concentric gap, permanent magnet field direct current instruments and crosses the active flux gap 3 in a radial direction over an arc of some 300 degrees at a uniform density if the air gap is made uniform. Special scale distributions may make it desirable 60 to use an air gap which varies from uniformity. The field flux enters the central magnetic core 6 through the tongue part at 5.

65 In assembling the instrument the armature is first assembled on its plug 13 while removed from the field structure. This is done by first assembling and positioning the jewels 18 and 19 in the bore of plug 13. The coil frame with its coil, pivots, balance weights, pointer and lead-in connections, is then assembled on the plug by first 70 passing the short side 24a of the coil through the

gap at 12 and then orienting the coil until its pivots are in line with the jewels. The screw 22 is loosened to allow the spring 23 to push jewel 18 outward until the proper pivot pressure is obtained with the pivots 20 and 21 seated in their jewels 18 and 19. Screw 22 is then tightened. This armature may be approximately balanced and the assembly is then inserted into the field structure. In so doing the plug 42, Fig. 3, if present, is first removed and the coil 9 oriented until its long side 24 is in line with gap 7 in core part 6, and the plug is lined up with the central opening in the core. The armature assembly plug is then moved endwise into place and the screws 16 are put in and tightened. The frame parts 35 and 32 with the parts carried thereby are then added. The spirals 29 and 30 are then connected at their outer ends to the crank arms for that purpose carried by the hubs such as 31. The spirals are then rotatively adjusted to position the instrument at approximately the zero scale position and are connected up with the circuit which is to energize the armature coil. The scale plate is added and the pointer set on zero with the zero set 38. A final adjustment for armature balance is made if necessary.

In the operation of the instrument only the long side of the coil moves in a flux gap 3, as there is no flux in the inner concentric gap 12. The operation is otherwise the same as for instruments having a coil side next to the shaft on the axis of rotation.

The armature assembly plug arrangement represented in Fig. 3 is the same as that explained in connection with Figs. 1 and 2 and is shown stripped of many of the instrument parts to more clearly indicate the important novel features.

Figs. 4, 5, and 6 represent another embodiment of my invention which differs primarily from the instrument previously explained by employing a removable inner magnetic core and internal pivot support made in one piece of magnetic material separable from the remainder of the magnetic circuit. This structure is best shown in Figs. 5 and 6 and comprises the outer C-shaped core part 42 which corresponds to part 6 of Fig. 3, the inner internal pivot support part 43 which corresponds to part 13 of Fig. 3, and the tongue part 44 which corresponds to part 14 of Fig. 3. The gap for inserting the short side 24a of the coil 9 into the inner gap 12 is provided at 45 before the core is secured to a frame part 46 by screws 47. The core part 42 is provided with outwardly projecting spacer parts 48 on either side of the gap 45 and frame strap 46 to make good magnetic contact with the tongue 5 of the permanent magnet field structure and to correctly position the core part 42 concentric with the inner pole shoe 2 of the field structure. The gap 45 and spacer lugs 48 are on the opposite side of the axis of rotation from the inner tongue 44 and are symmetrical with respect to the center line of such tongues. The frame part 46 is held in place by bolts 49 passing through holes in the tongue 5. The bolts 49 and the strap 46 are preferably made of magnetic material to reduce the reluctance to flux flow from tongue 5 to core part 42. The remainder of the instrument construction is essentially similar to that previously described in connection with Figs. 1 and 2 and need not be again described.

In assembling the instrument of Figs. 4, 5, and 6, the armature coil frame and parts carried thereon are assembled in core part 43 before this part is fastened to frame part 46. The short coil

side 24a is passed through gap 45 edgewise and the coil 9 is turned to the position shown in the drawing and then mounted on its jewels in the same manner as explained in connection with Fig. 2. Core 42 is then secured to the frame composed of parts 46 and 32, and the spirals are connected up and adjusted before these parts are inserted into the field structure. Then the frame with the armature assembly thereon is inserted into place in the field structure and bolted in place by the bolts 49. While in Figs. 5 and 6 the inner jewel support 43 is generally made of magnetic material, there is no tendency for flux to flow across gap 12, as parts 42 and 43 are of the same magnetic potential. The advantages previously mentioned in connection with Figs. 1 to 3 are present in the construction of the instrument of Figs. 4 to 6.

While I have shown a particular embodiment of my invention, I do not desire my invention to be limited to the particular construction shown and I intend in the appended claims to cover all modifications within the true spirit and scope of my invention.

What I claim as new and desire to secure by Letters Patent of the United States is:

1. An electrical measuring instrument comprising a field magnet including a C-shaped magnetic part, a circular outer magnetic part united to the outer surface of the C-shaped part and with a tongue of magnetic material extending radially inward within the opening in the C-shaped part, and a magnetic core part within the C-shaped part and magnetically united with the tongue part, the inner surface of the C-shaped part and the outer surface of the core part defining a circular air gap of the order of 300 degrees in arc length, at least a portion of said field magnet being made of permanent magnet material and polarized to produce flux across said gap, said core part having an interior circular opening and a bearing support centrally within said opening positioned in place by a tongue secured between it and the core part on a radius diametrically opposite to that of the previously mentioned tongue of magnetic material, said structure providing an inner circular air gap about the bearing support concentric with the first-mentioned air gap and of approximately the same arc length, and an armature coil having internal pivots mounted for rotation in said bearing support with opposite coil sides thereof in said respective air gaps.

2. An electrical measuring instrument comprising a field magnet including a C-shaped magnetic part, a circular outer magnetic part united to the outer surface of the C-shaped part and with a tongue of magnetic material extending radially inward within the opening in the C-shaped part, and a magnetic core part within the C-shaped part and magnetically united with the tongue part, the inner surface of the C-shaped part and the outer surface of the core part defining a circular air gap of the order of 300 degrees in arc length, at least a portion of said field magnet being made of permanent magnet material and polarized to produce flux across said gap, said core part having an interior circular opening and a bearing support centrally within said opening positioned in place by a tongue secured between it and the core part on a radius diametrically opposite to that of the previously mentioned tongue of magnetic material, said structure providing an inner circular air gap about the bearing support concentric with the first-mentioned air gap and

of approximately the same arc length, and an armature coil having internal pivots mounted for rotation in said bearing support with opposite coil sides thereof in said respective air gaps, said core part having a radial opening to permit passage of a side of the coil therethrough during assembly.

3. An electrical measuring instrument comprising a field magnet including a C-shaped magnetic part, a circular outer magnetic part united to the C-shaped part and with a tongue of magnetic material extending radially inward within the opening of the C-shaped part, and a magnetic core part within and spaced from the C-shaped part and magnetically and mechanically but removably united with said tongue part, the adjacent surfaces of the C-shaped and core parts defining a circular air gap extending over an arc greater than 180 degrees, at least a portion of said magnetic circuit being of permanent magnetic material and polarized to produce a flux across said air gap, said core part having an interior circular opening and a bearing support centrally within said opening secured in place by a tongue between it and the core on a radius diametrically opposite to that of said previously mentioned tongue, said tongue and bearing support being formed integral with said core part and of the same material, said structure forming an inner circular air gap about the bearing support concentric with said first-mentioned gap and of approximately the same arc length, and an armature coil having internal pivots mounted for rotation in said bearing support on an axis concentric with said air gaps, said coil having one side in the first-mentioned gap and the other side in the second-mentioned gap, said core having a radial gap adjacent the point where united to the first-mentioned magnetic tongue to permit a side of said coil to be passed therethrough into the inner air gap during assembly when said core part is removed from remainder of the magnetic field.

4. An electrical measuring instrument comprising an inner cylindrical core, an outer magnetic yoke having a radially inwardly projecting magnetic tongue united to the core and a C-shaped magnetic part between the core and yoke but separated from the core to provide a circular air gap between the inner surface of the C-shaped part and the outer surface of the core, a considerable portion of said C-shaped part being of permanent magnet material and polarized radially to produce a flux across said gap, said cylindrical core being hollow, a removable plug fitted into said hollow core, said plug having an outer cylindrical shell and an inner central bearing support joined to the shell by a radial tongue, said plug thus containing an inner circular air gap concentric with the first-mentioned air gap, said gaps extending over arcs of the order of 300 degrees length, means for securing said plug in said core with its tongue diametrically opposite to the first-mentioned magnetic tongue, and an armature coil surrounding the bearing support portion of said plug and rotatively supported thereon on an axis concentric with said gaps and with one side of the coil in the outer flux air gap and the other side of the coil in the inner air gap, said core and shell of said plug having radial slits therein for the purpose of passing one side of the coil therethrough.

5. An electrical measuring instrument having inner and outer concentric air gaps, each of an arc length of the order of 300 degrees, a magnetic circuit for producing a flux across the outer gap, said magnetic circuit having inner and outer pole piece portions which define the outer gap, an armature including a coil pivoted for rotation on an axis concentric with said air gaps, and with one of its coil sides in the outer gap and its other coil side in the inner gap, a bearing support within in said coil on the axis of rotation thereof, and on which said coil is rotatively supported, supporting structure for the bearing support and portion of the magnetic circuit contained within said coil which supporting structure includes a radial tongue portion defining the length of the outer gap and a second radial tongue portion defining the length of the inner gap, said radial tongue portions being positioned on diametrically opposite sides of the axis of rotation of the coil so as to obtain the maximum free arc of rotation for said coil, said armature, bearing support, and at least a portion of said supporting structure being removable as a unit from within the outerpole piece portion of said magnetic circuit.

6. An electrical measuring instrument having a magnetic circuit comprising a C-shaped part, a hollow cylindrical core part within the C-shaped part and an outer circular yoke and a radial tongue part joining the C-shaped part to the core part, a circular air gap of the order of 300 degrees between the C-shaped and cylindrical core parts, at least a portion of said magnetic circuit being of permanent magnet material and polarized to produce a flux across said air gap, an armature having a coil one side of which is positioned in said air gap, a support containing jewels within said core parts, internal pivots on said armature supported in said jewels whereby the armature is rotatively mounted on an axis concentric with said air gap, said jewel support being spaced from the inner wall of the hollow core part to provide a second circular air gap concentric with the axis of rotation to accommodate the other side of said coil, and a supporting tongue for said jewel support between it and the core on a radius opposite to that of the radial tongue part of the magnetic circuit, said core part and rotatively mounted armature being removable from within the remainder of the magnetic circuit and said core part having a radial opening adjacent the point where it joins with the remainder of the magnetic circuit for the purpose of permitting one side of the coil to be passed therethrough.
